STEPHEN M. DONALDSON.

By Thomas R. Harvey

Attorney

UNITED STATES PATENT OFFICE.

STEPHEN M. DONALDSON, OF MEGGETT, SOUTH CAROLINA.

RAILROAD SIGNAL.

Application filed January 29, 1923. Serial No. 615,703.

To all whom it may concern:

Be it known that I, STEPHEN M. DONALDSON, a citizen of the United States of America, residing at Meggett, in the county of 5 Charleston and State of South Carolina, have invented certain new and useful Improvements in Railroad Signals, of which the following is a specification.

My present invention relates to improvements 10 in railroad signals for the protection of grade crossings at highways, and involves both a visual and audible signal actuated by energy from an approaching train or locomotive. The invention as embodied herein is illustrated in connection with a 15 single track railway, and the signals are adapted for actuation upon the approach of a train from either of the two directions, but it will be understood that the signal mechanism may be adapted for use on double 20 track railways when required.

The invention contemplates the use of a signal tower located in proper position at a highway, grade crossing over the railroad, 25 in which tower the operating mechanism and the audible signal, or bell, are supported, together with the visual signal or flag. By means of the train actuated mechanism the bell is sounded and the flag waved at the 30 approach of a train as a warning signal, as will be hereinafter pointed out and claimed.

In the accompanying drawings I have 35 illustrated one complete example of the physical embodiment of my invention as an equipment for a single track railroad, wherein the parts are combined and arranged according to one mode I have devised for the practical application of the principles of my invention.

Figure 1 is a view elevation of the signal tower, showing in dotted lines the movement 40 of the visual signal or flag when actuated upon the approach of a train.

Figure 2 is an enlarged, vertical sectional view of the signal tower, part of the signal arm or flag supporting member being broken away at the top.

Figure 3 is a detail perspective view of 50 the bell tapper, showing its suspension means from the signal arm.

Figure 4 is a vertical sectional view of the signal tower, as seen from the right in Figure 2.

Figure 5 is a detail view showing one of 55 the tripping dogs, with its housing or box

in section, and illustrating its relation to the railway track rail;

Figure 6 is a detail view of one of the 60 roller supports for the draw rod of the signal.

Figure 7 is a horizontal sectional view at the base of the signal tower, showing the actuating levers and connections.

Figure 8 is a view in side elevation of one 65 of the tripping dogs, with parts in section.

Figure 9 is a diagrammatic view showing the grade crossing and railroad tracks, and relative position of the signal equipment.

The standard ties 1 and rails 2 are illustrated and so much of a single track railway is shown as is necessary for an understanding of my invention, it being understood that the duplex actuating mechanism at the sides of the grade crossing is actuated by an approaching train through the instrumentality of a tripping dog as 3, located 70 above the railway ties, and at the track side. The tripping dog is provided with a slotted housing 4, and the dog is pivoted to oscillate on an axle or shaft 5 supported in the plate 6 that is attached to adjoining ties as usual. The tripping dog is fashioned with a weighted portion or weight 7 to maintain it normally in upright or vertical position at the outer side of the track rail 2, as indicated 75 in Figure 5.

A pair of laterally projecting trunnions 8 are fashioned on the tripping dog, below its 80 pivotal point, for co-action with the draw rod 9. The tripping dog is preferably of metal and of course of sufficient strength to withstand the shocks to which it will be subjected, while the draw rod 9 [one at each side of the crossing] may be made of pipe 85 sections in usual manner. The draw rod contacts with the trunnions of the tripping dog 90 through the instrumentality of a bifurcated hook 10 which is designed to engage the trunnions in such manner that the rod will be drawn to the right in Figure 8 for a

working stroke, and will permit the tripping dog to swing freely on an idle stroke imparted to the dog. The hook is fashioned 100 with a socket head 11 secured as by screw threads on the draw rod, and this head engages against an abutment 12 inside the housing when the draw rod is in normal position.

The tripping dog is rocked or swung on 105 its pivot 5 by impact from a trip arm 13 110

carried, as indicated by dotted lines in Figure 5, by the locomotive, which moves in the direction indicated by the arrow in Figure 8 to ride down the tripping dog, and through 5 the trunnions and hook, the swinging motion of the tripping dog is converted to a draw motion of the draw rod 9. The latter is guided in bearing brackets or plates 14 located at suitable intervals along the track 10 side, and it will be understood that the two tripping dogs are positioned at the proper distance from the grade crossing to give ample time for the signalling of the approaching train. For supporting the draw 15 rods throughout their length, anti-friction rollers 15 may be attached to the ties at suitable intervals.

The adjoining ends of the draw rods terminate at one side of the highway crossing, 20 and each rod is provided with a spring 16 which is interposed between a collar 17 fixed on the draw rod and a bearing bracket 18 through which the draw rod may reciprocate or slide. The collar forms an abutment 25 and is held against the bearing bracket 19 for the draw rod, and it will be apparent that the draw rod, in Figure 7, may be pulled to the right to compress the spring, and after the trip arm of the locomotive has passed 30 over the tripping dog and released the latter, the spring, by expansion pulls the draw rod to the left at the right side of Figure 7, thus restoring the draw rod to normal position.

35 The adjoining ends of the draw rods are each equipped with a pivoted extension in the form of a link as 20 and 21, and each link is pivoted to an angular lever arm as 22 and 23. The lever arms are disposed in parallelism at right angles to the draw rods and pivoted at 22' and 23' respectively to swing in horizontal planes, the pivoted links 20 and 21 being connected in such manner as to permit the draw rods to swing their respective lever arms as one or the other of the draw rods is actuated.

40 Each lever arm is fashioned with a pivoted extension, as 24 and 25, and these extensions are pivoted to their respective arms at 26 in order that they may swing slightly in a vertical plane as they are carried by the lever arms when the latter swing in their horizontal planes. This double pivot arrangement enables the free ends of the lever arms to be elevated slightly as the lever arms are swung on their pivots in one direction, or 45 the working stroke, and said extensions are depressed on their idle or return strokes.

46 This movement of the pivoted extensions of the lever arms is imparted thereto through a guide plate 27 and its guide slot 28, the plate being located in position at right angles to the pivoted levers and their extensions, and the upper and lower walls of 50 the slot being slightly inclined as required.

In Figures 2 and 7 it will be seen that when the lever arm 23 is actuated by the draw rod 9, the pivoted extension 25 will be swung to the left. As said extension is swung to the left it rides up the curved and upwardly inclined portion of the slot 28, at the right of the center of the slot in Figure 2, and of course upon its return movement the extension rides down the slot walls to normal position as indicated in these figures of drawing 75 2 and 7.

This movement of the pivoted extension is utilized in connection with and to impart movement to a pendulum or oscillating arm 29, which is supported to swing on its trunnions 30 in the bearings 31. The bearings are supported in a frame 32, and a housing or tower encloses the oscillating arm and its connections, said housing being indicated by the numeral 33. It will be apparent that the lower end of the pendulum or oscillating arm is located in the path of either of the two lever extensions 24 and 25, and that when either of these extensions is actuated it will rise to the proper elevation to contact with the free end of the oscillating arm and swing the latter on its trunnions. One stroke of the lever extension is sufficient to set in motion the oscillating arm, and immediately the lever extension is returned to 95 normal position, the oscillating arm however swings until returned to normal position by gravity.

For varying the length of the stroke of the pendulum and thereby increasing or decreasing the rapidity of its movement, I provide 100 a weight 34, which moves between guides 35 fixed at the inner sides of the housing, and the weight may be supported in adjusted position by a cotter pin 36 inserted through 105 one of the several holes 37 in the arm.

Through the oscillating movement of the suspended arm 29 the audible signal is sounded by means of a bell 38 which is supported from the fixed bracket 38' near 110 the top and inside of the tower 33. A bell tapper or ball 39 is suspended by a suitable suspension device 40 from the oscillating arm at 41 above the bell, and the tapper hangs in proper position to swing and contact with the bell for ringing the latter as the tapper swings back and forth with the oscillating arm. A guide bracket 42 is attached to the oscillating arm and provided with a guide slot for the suspension device 115 of the tapper, to restrain and guide the bell tapper in its movements.

120 The visual signal is carried at the upper end of the oscillating arm, which passes through a slot 43 in the top of the tower, and a flag 44 of usual type is attached at the upper end of the oscillating arm. Said flag is waved back and forth as indicated in dotted lines in Figure 1 when the signal is actuated.

Other necessary accessories, while not illustrated will of course be supplied, as for instance slots 45 in the wall of the tower are used to permit movement of sound waves from the bell, and doors as 46, 47, 48, are provided to give access to the interior of the tower when required.

From the above description taken in connection with my drawings it will be apparent that I have provided a signal installation of this type which is comparatively simple in construction, durable, and efficient in performing its required functions.

Having thus fully described my invention, what I claim and desire to secure by Letters Patent is:—

1. The combination with an oscillatable signal arm, of a pivoted lever adjacent to the free end of said arm, a draw rod operatively connected to said lever, and a vehicle actuated tripping dog operatively connected to said draw rod, and means for guiding said lever into contact with the free end of said signal arm to move the latter upon actuation of said tripping dog.

2. The combination with an oscillatable signal arm, of a pivoted lever normally out of operative position with relation to the free end of said arm, a draw rod connected to said lever and means for retaining said rod in normal position, a vehicle actuated tripping dog operatively connected to the draw rod, and means for guiding said lever into position for contact with the free end of said signal arm upon a working stroke of said tripping dog.

3. The combination with an oscillatable signal arm, of a pivoted lever arm, a draw rod and tripping dog, a pivoted extension on said lever arm, a plate adjacent said signal arm, and said plate having an in-

clined slot for said extension whereby the latter is guided for impact with said signal arm when the tripping dog is actuated.

4. The combination in a railway signal with a pivoted vehicle actuated tripping dog having oppositely disposed trunnions, of a draw rod and a socket head thereon, and a bifurcated hook on said head loosely engaging said trunnions whereby the dog may operate the draw rod on its working stroke and swing free of the hook on its return stroke.

5. The combination in a railway signal with a pivoted vehicle actuated tripping dog having oppositely disposed trunnions and a weight on said dog for normally holding the latter in operative position, of a draw rod and head thereon, and means on said head operatively connected to said trunnions whereby the dog may operate the rod on its working stroke and by gravity return to normal position, and swing freely on an idle stroke.

6. The combination in a railway signal with an oscillatable arm and vehicle actuated means for swinging said arm, of a stationary bell, a tapper suspended on said arm in position to strike the bell when the arm is oscillated, and means carried by said arm for guiding said tapper.

7. The combination in a vehicle actuated signal including an oscillatable arm, of a stationary bell, a tapper in position to strike said bell, a flexible suspension member on said arm for said tapper, and a slotted guide plate carried by said arm for said member.

In testimony whereof I have affixed my signature.

STEPHEN M. DONALDSON.
